UNITED STATES PATENT OFFICE.

JAMES S. STEELE, OF PITTSBURG, PENNSYLVANIA.

FEED-WATER REGULATOR AND LOW-WATER ALARM.

SPECIFICATION forming part of Letters Patent No. 570,066, dated October 27, 1896.

Application filed March 2, 1896. Serial No. 581,453. (No model.)

To all whom it may concern:

Be it known that I, JAMES S. STEELE, a citizen of the United States of America, residing at Pittsburg, in the county of Allegheny and State of Pennsylvania, have invented certain new and useful Improvements in Feed-Water Regulators and Low-Water Alarms, of which the following is a specification, reference being had therein to the accompanying drawings.

This invention relates to certain new and useful improvements in regulators, and relates more particularly to that class known as "feed-water regulators."

The invention has for its object the provision of new and novel means whereby the gage of the water in the boiler may be readily determined by the construction of a regulator that will automatically give an alarm when the water reaches the low-water mark.

A still further object of the invention is to construct a feed-water regulator, as above described, that can readily be placed in position on any boiler or series of boilers; furthermore, that will be extremely simple in its construction, strong, durable, effectual in its operation, and comparatively inexpensive to manufacture.

With the above and other objects in view the invention finally consists in the novel construction, combination, and arrangement of parts to be hereinafter more specifically described, and more particularly pointed out in the claims.

In describing the invention in details reference is had to the accompanying drawings, forming a part of this specification, and wherein like letters of reference indicate similar parts throughout the several views, in which—

Figure 1 is a vertical sectional view of a portion of the boiler, showing my improved feed-water regulator in position. Fig. 2 is a side elevation of my improved regulator. Fig. 3 is a vertical sectional view of the same. Fig. 4 is an enlarged side elevation of a portion of the operating-levers.

In the drawings, *a* represents the feed-water pipe, to which is secured, within the boiler *b*, the valve *c*. The casing of this valve *c* is formed at the front with lugs *d d* at each side, to which is secured by means of bolts *e*

e a plate *f*, formed with an inclined opening against which the plug *g* rests. This plug *g* is formed with a square, octagon, or other suitably-shaped outer end *h*, which is adapted to receive the boss *i*, formed on the arm *j*. This arm is bent downward slightly, and carries on its lower end a float *k*, which may be composed of copper or other suitable material, and the portion of the arm *j* that extends on the other side of the boss *i* is provided with an aperture, which is adapted to receive an upright rod *l*, having an adjustable collar or sleeve *m*, adapted to rest on the arm *j*. The plate *f* is provided with an upwardly-extending portion *f'*, on which is formed an angle-shaped portion *f''*. This angle-shaped portion is provided with an aperture which receives the upright rod *l* and retains the same in a vertical position. Underneath this portion is pivotally secured to the vertical rod *l* an arm *n*, which is also pivotally connected at the inner edge of the upwardly-extending portion *f'* and to the operating-rod *o* of the valve *p*, connected to the steam-pipe *q*, which is provided with a whistle *r* to give an alarm when the low-water line is reached, as will be hereinafter more fully explained.

The operation of my improved automatic feed-water regulator is as follows: When the parts have been secured in their respective positions, as shown in the drawings, the water is fed to the boiler through the feed-pipe *a* until the desired quantity is obtained in the boiler. When the boiler is empty, the float *k* will be suspended in alinement with the feed-water pipe, which will operate the plug *g*, bringing the opening in alinement with the pipe and allowing the water to pass through the valve. As the water rises in the boiler it will raise the float *k*, automatically closing the valve until the supply of water is shut off. As the water in the boiler becomes heated and begins to recede the float *k* will descend therewith until the low-water mark is reached, causing the upper end of the arm *j* to raise the vertical rod *l*, lifting the cross-arm *n*, which in turn raises the operating-rod *o* of the steam-valve and allowing the steam to pass into the steam-pipe to the alarm-whistle *r* and giving the alarm to the engineer or attendant.

It will be noted that my improved automatic feed-water regulator and alarm will be

particularly useful in cases where it is impossible for the engineer to be in attendance at the boilers at all times, as should the danger or the low-water line be reached when the 5 engineer is absent the alarm will be given by the whistle, and the water can be turned on in the boiler before any danger is caused to the boiler.

It will also be noted that no special construction is required which will prevent the 10 attachment of my improved regulator to any boiler or series of boilers now in use, and by relieving the engineer of the necessity of watching the stage of the water in the boiler 15 will allow him to devote more time to the engine, &c.

It will also be noted that various changes 20 may be made in the details of construction of my improved automatic feed-water regulator 25 and alarm without departing from the general spirit of my invention.

Having fully described my invention, what I claim as new, and desire to secure by Letters Patent, is—

25 1. In an automatic feed-water regulator, a valve attached to the feed-water pipe within the boiler, an arm having a boss adapted to

engage on the plug of the valve, said arm having a float secured to its lower end and having an aperture in its upper end adapted to 30 receive an upright rod provided with a pivotally-attached cross-arm secured to the operating-rod of the steam-valve, substantially as shown and described.

2. In a regulator for boilers, a valve secured to the feed-water pipe, said valve having a front plate which retains the plug in position and provided with an upwardly-projecting portion carrying an angle-plate, in combination with an operating-arm attached 40 to the plug and having a float on its lower end and supporting an upright rod on its upper end, said rod having an adjustable collar, a cross-arm pivotally attached to the upright rod and to the projecting portion of the plate 45 and operating-rod of the steam-valve, substantially as shown and described.

In testimony whereof I affix my signature in presence of two witnesses.

JAMES S. STEELE.
